UNITED STATES PATENT OFFICE.

SAMUEL T. LOCKWOOD, OF PORTLAND, OREGON.

BAG-HOLDING MECHANISM FOR BAG-TURNING MACHINES.

No. 846,118.

Specification of Letters Patent.

Patented March 5, 1907.

Application filed January 15, 1906. Serial No. 296,181.

To all whom it may concern:

Be it known that I, SAMUEL T. LOCKWOOD, a citizen of the United States, of Portland, in the county of Multnomah and State of Oregon, have invented certain new and useful Improvements in Bag-Holding Mechanism for Bag-Turning Machines; and I do hereby declare that the following is a full, clear, and exact description thereof, reference being had to the accompanying drawings, and to the letters of reference marked thereon, which form a part of this specification.

This invention relates to improvements in bag-turning machines of the general type shown in my prior United States Letters Patent, No. 777,427, granted December 13, 1904; and the invention relates more specifically to improvements in the bag-holding mechanism by which the bag is held preparatory to the turning operation and to the means for operating said holding mechanism to open the bag-mouth to receive the turning-arms.

Among the principal objects of my invention is to provide means for releasing the tension exerted by the bag-holders upon the mouth of the bag after the bag has been partially turned and before the turning-arms are brought into contact with the bag-bottom, and thereby facilitating the release of the bag from the holders and avoid liability of the bottom of the bag being punctured by the bag-turning arms.

A further object of the invention is to provide a tension releasing or slackening mechanism of this character which may be adjusted to bags of various lengths.

A still further object of the invention is to provide an improved mechanism for imparting a step-by-step rotation to the bag-holders when using holders of the character shown in my aforesaid prior Letters Patent.

Another object of the invention is to provide means for arresting the rotation of the bag-holders after the same have been rotated the required angular distance, and thereby avoid overthrow of the holders due to their momentum when the holders are turning idly and without the bags thereon.

Other objects of the invention will appear from the following description, and the invention is set forth in the appended claims.

In the drawings, Figure 1 is a top plan view, partially broken away, of one end of a bag-turning machine embodying my improvements. Fig. 2 is a partial side eleva-

tion and partial vertical longitudinal section thereof. Fig. 3 is a transverse vertical section taken through the frame that supports the carriage which carries the bag-turning arms looking toward the bag holding and pressing mechanism. Fig. 4 is a detail illustrating a portion of one of the bag-holders, its operating-shaft, and bearing therefor. Fig. 5 is an end elevation of the machine with the fly and fly-frame removed. Fig. 5^a is a detail illustrating the gearing for driving the stripper-rollers. Fig. 6 is a cross-section taken on line 6 6 of Fig. 8. Fig. 7 is a detail in side elevation, illustrating the mechanism for operating the bag-holders. Fig. 8 is a front elevation of one end of the bag-holders, showing a portion of the mechanism for operating the same in section, the latter section being taken on line 8 8 of Fig. 6. Fig. 9 is a view, partially in side elevation and partially in section, showing the bag-holder-operating mechanism and pressing-rollers. Fig. 10 is a detail illustrating means for varying the tension of the holder-actuating mechanism. Fig. 11 is a sectional detail of the time-shaft and cam thereof for relieving the tension on the bags while on the holder.

The machine herein shown is of that type known as a "double" machine, or one wherein the single actuating mechanism for the carriage operates two pairs of turning-arms extending oppositely from the central carriage or support and cooperates with two bag holding and pressing mechanisms located one at each end of the carriage-frame. My improvements may, however, be employed in a machine having but a single bag holding and pressing mechanism.

As shown in the drawings, 12 indicates as a whole the frame for supporting the centrally-located carriage (not shown) that carries the bag-turning arms 13. The frame for the bag-holders and pressing-rollers embraces vertical standards 14 14, which carry the bearings for the shafts of the stripper-rollers and pressing-rollers and upper and lower longitudinal rails 15 16, respectively. The upright frame members are connected at their upper ends by a transverse member 14^a.

17 designates the main shaft of the machine mounted in bearings in the standards 14 and provided at one side of the machine with fast and loose belt-pulleys 18 19. When the machine is provided with two bag-holding and pressing mechanisms, such mechanism on

the end of the machine opposite that shown is operated from the main shafts 17 through the medium of a horizontal shaft 20, extending longitudinally of the machine and connected with the shafts 17 through the medium of intermeshing gears 21 22, respectively.

23 designates a counter-shaft, hereinafter termed the "time-shaft," mounted in the standards 14 below the main shaft 17 and driven from said main shaft 17 through the medium of a pinion 24 on the main shaft and a gear-wheel 25 on the counter-shaft, Figs. 3 and 5.

26 26 designate the pressing-rollers, the shafts of which are mounted in bearings supported on the upper parts of said standards 14. The shafts of said pressing-rollers 26 extend outside of the standards at one side 20 of the frame and are provided with intermeshing gear-wheels 27 27, the lower one of which has meshing engagement with a gear-wheel 28, Figs. 3 and 5, fixed to the outer or adjacent end of the main shaft 17, whereby 25 said pressing-rollers are driven from the main shaft. Located in front of said pressing-rollers are stripper-rollers 30 and 31, the shafts 32 32^a of which are mounted in bearings carried by the standards 14. The 30 shaft 32 of the lower roller is provided at one side of the machine, outside of the standard 14, with a pinion 33, Fig. 5^a, which meshes with a pinion 34, mounted on a stub-shaft 35, fixed in said standard and driven by a gear-wheel 36, fixed to the adjacent end of the shaft of the lower pressing-roller 26. The 35 shafts of the upper and lower stripper-rollers are provided at the opposite side of the machine with meshing rollers 37 38, Fig. 5, whereby 40 by the upper stripper-roller is driven from the lower roller. The lower stripper-roller comprises, as herein shown, a continuous roller, while the upper stripper-roller comprises two short roller-sections which are fixed on the 45 shaft 32^a. Said upper roller-sections are adapted to be moved toward and from each other, as will hereinafter be described, for the purpose of adjusting the machine to bags of different widths.

50 40 designates the fly by which the turned and pressed bags are removed from the pressing-rollers. Said fly is fixed to a rock-shaft 41, that is mounted in an extension-frame 42 and is operated by a cam 43 on the 55 time-shaft, a swinging lever 44, pivoted at its upper end to the machine-frame and provided between its ends with a roller 45, engaging the periphery of said cam, and a pitman or connecting-rod 46, connected at one 60c end with the lower end of said lever and at its other end, through the medium of a crank 47, with the rock-shaft 41. The fly is drawn to its uppermost position by the cam and is restored to its lowermost position by a spiral 65 spring 48, surrounding an endwise-recipro-

cating rod 49, hinged at one end to said crank-arm 47 and having guiding engagement with the frame of the machine, said spring 48 being interposed between the guide 50 for the rod on the machine-frame and a 70 nut 57 on the rod.

52 52 designate as a whole the bag-holders, made generally like the bag-holders shown in my aforesaid prior patent, No. 777,427. Said holders consist of two flat rotative 75 plates 52^a 52^a, rotating in vertical planes and located one on each side of the longitudinal center of the machine and provided with inwardly-extending bag-holding arms 53, three being herein shown, which extend toward 80 the retracted position of the bag-turning arms. The arms of the two holders operate in pairs—that is to say, the mouth of the bag is adapted to be placed over and held by two corresponding arms of the two holders 85 when located, by reason of their rotation, close to each other, and as such holders rotate, said arms are separated in a manner to spread or distend the mouth of the bag and to hold the same spread in position for the 90 turning-arms to turn the body of the bag therethrough. While one pair of said arms thus holds one bag distended another pair is in position to receive another bag, which in the subsequent rotation of the holders is 95 stretched and brought into line with the turning-arms. A step-by-step rotation is imparted to said holders, which move the corresponding arms of the two holders successively into and out of their operative positions. The said plates 52^a of the holders are mounted on short shafts 54, Fig. 4, which have bearing in blocks 55, mounted on and movable endwise of a horizontal stationary shaft 56, which extends transversely across 100 the machine and is fixed at its ends in standards 57, that rise from the upper horizontal rails 15 of the machine-frame. As herein shown, the plates 52^a of the bag-holders are fixed to the shafts 54 through the medium of flanged sleeves 58, keyed to the shafts 54 and provided in their flanges 59 with curved slots 60, (indicated in dotted lines in Fig. 8,) through which extend screw-bolts 61, that have screw-threaded engagement with apertured holes in the plates 52^a. The curved slots 60 are intended to permit angular adjustment of the holder-plates with respect to their shafts. The said holder-plates 52^a have also central screw-threaded apertures, 110 and the shafts 54 are provided with reduced screw-threaded extensions 62, that have screw-threaded engagement with said plates. The said shafts are provided with beveled pinions 63, by which power is transmitted to 115 the holders.

64 designates a horizontal transversely-disposed shaft that is rotatively mounted in brackets 65, extending rearwardly from the standards 57, Figs. 1 and 7. Said shaft 64 130

carries two beveled pinions 66 66, which mesh with the gear-pinions 63 of the holder-shafts 54 and are splined to said shaft to move endwise thereof. As herein shown, 5 the shafts 54 and the holders carried thereby, as well as the beveled gears 66 on the shafts 64, are moved toward and away from each other in order to adapt the machine to bags of different widths. For this purpose each 10 shaft-bearing 55, which is mounted on the transverse rod 56, before referred to, is provided with arms 67 67, which extend outwardly or rearwardly from said bearings and are apertured at their outer ends to fit over 15 the rotary shaft 64 on opposite sides of the adjacent beveled gears 66. Said beveled gears are provided with elongated hubs 68, against the end of which one of the arms 67 bears, and short sleeves 69 are interposed between 20 the gears and the other arms, whereby movement of said bearings and their arms on the shaft 56 imparts a positive movement to the gear-pinions 66 on the shaft 64. The said parts are adjusted toward and from each 25 other for the purpose stated by means of a rotative right and left handed screw-threaded shaft 71, Figs. 1, 4, and 9, located transversely above and parallel with the supporting-shaft 56 and mounted at its ends in the 30 upper ends of the standards 57, Figs. 7 and 8. Said bearings 55 are provided with apertured screw-threaded lugs 72, rising therefrom, through which extends the screw-threaded shaft 71, whereby rotation of said screw-shaft acts, through the lugs 72, to move the 35 bearings 55 toward and from each other on the supporting-shaft 56 and also the driving-pinions 66 of the shafts 64 in unison therewith. It is desirable also that the upper 40 stripper-rollers 31 be adjusted on their shaft 32^a toward and away from each other to correspond with the adjustment of the bag-holders. For this purpose arms 75 extend rearwardly from the laterally-movable bearings 55, as shown in Fig. 1, and are provided 45 at their rear ends with nuts 76, which are mounted on a rotative right-and-left screw-threaded shaft 77, located in front of and parallel with the stripper-rollers, and 50 said arms 75 extend beyond the screw-shaft 77 and enter annular grooves 78, formed in extensions or hubs of the short upper stripper-rollers 31. The rotative screw-shaft 77 is mounted at its ends in bearing-standards 55 55 79 on the side rails 15 of the machine. The shafts 71 and 77 are provided at their corresponding ends with pulleys 80 and 81, herein shown as having the form of sprocket-pulleys, which are connected by a sprocket-belt 82, and the shaft 71 is provided with a 60 crank 83, by which simultaneous rotary motion is imparted to said shafts to effect simultaneous lateral adjustment of the holders and the stripper-rollers.

65 Referring now to the mechanism for im-

parting a step-by-step rotary movement to the shaft 64 from the time-shaft 23, and thereby intermittently rotate the holders for the purpose specified, such mechanism is made as follows: The bag-holder bearing 70 supporting-shaft 56 extends beyond the standard 57 at one side of the machine and is provided on its extended end with a rotative sleeve 85, fixed from endwise movement between said standard and a plate 86, that is 75 attached to the shaft by means of a central screw-bolt 87, extending through the plate and having axial screw-threaded engagement with the shaft, Fig. 8. The sleeve 85 is provided on its inner end with a gear-wheel 88, 80 that meshes with a gear-pinion 89, fixed to the adjacent end of the holder-actuating shaft 64, Figs. 1, 7, and 9. Said sleeve 85 is also provided just outside of the gear-wheel 88 with a plurality of ratchet-teeth 90, as 85 best shown in Fig. 6, which are adapted for engagement by a spring-pressed pawl 91, carried by an arm 92, rigid with and extending radially from a collar 93, rotatively mounted on said sleeve 85, Fig. 8. The said collar 93 90 is provided with a second rigid arm 94, that is pivoted at its outer ends to an upright link 95, Figs. 1 and 9, near the upper end of the latter, by means of a pivot-pin 96, and said link is operatively connected at its lower 95 end with the time-shaft 23. As herein shown, said time-shaft 23 is provided with a suitable cam 100, which operates upon a rearwardly-extending vertically-swinging arm 97 of a horizontal rock-shaft 98, mounted transversely in the machine-frame, and the said rock-shaft is provided with an inwardly-extending arm 99, which is hinged to the lower end of the link 95. Preferably the rear end of the rock-shaft arm 97 is provided 100 with an antifriction-roller 101, which rides on the irregular periphery of the cam 100. The rock-shaft and its arms are placed under the influence of a spring 102, acting normally to hold the inner arm depressed and against the 105 force of which spring said inner arm is raised by the cam 100. Said spring, as herein shown, has the form of a spiral expansively-acting spring and surrounds a vertical rod 103, that is pivoted at its lower end to the 110 inner rock-shaft arm 99 and has guiding engagement at its upper end with the inner end of an arm 104, extending forwardly from a horizontal rock-shaft 105, that extends transversely across the machine and is mounted in suitable bearings 105^a. The spring 102 is compressed between the said arm 104 and a shoulder 106 at the lower end of said rod. As herein shown, the spring 115 bears at its upper end against a sleeve 107, and said sleeve is provided with outwardly-extending pins 108, against which the bifurcated members of the arm 104 bear. The tension of the spring is adapted to be adjusted, by means of a lever or arm 109, on the 120 125 130

side of the machine remote from the spring, which is fixed to the rock-shaft 105 and operates in connection with a suitable rack 110, fixed to the adjacent side of the machine, as clearly shown in Fig. 10.

With this construction it will be observed that when the inner end of the rock-shaft arm 99 is raised through the action of the cam 100 and against the action of the spring 102 the collar 93, operatively connected with the upper end of the link 95, is rocked on its bearings and acts, through the arm 92, to carry the pawl 91 backwardly over the ratchet-teeth 90 on the sleeve 85, and when said inner end of the rock-shaft arm 99 is depressed the link 95 is reciprocated downwardly and rocks the collar 93 in the reverse direction, thereby carrying the pawl 91 against one of the ratchet-teeth 90 and rocking said sleeve 95 a predetermined angular distance. This action of the pawl-and-ratchet mechanism operates to turn the sleeve 85 and its gear-wheel 88 and, through the shafts 64 and 54 and their intermeshing gears, to turn the holders the desired angular distance to present a distended bag to the turning-arms.

In order to prevent overthrow of the holders or to prevent them being turned too far 30 in each step of their movement at a time when no bags are applied thereto, a stop mechanism is provided which operates to arrest said holders in their proper positions, and thereby avoid the liability of the arms 35 of the holder stopping at such time in the paths of the turning-arms, with a result of an interference between such parts. Said stop mechanism may be conveniently made as follows:

40 112 designates a star-wheel which is fixed to the outer end of the sleeve 85, as best shown in Fig. 8, it being herein shown as having screw-threaded engagement with the reduced outer end of said sleeve. The teeth or 45 arms 113 of said star-wheel are straight or abrupt on the sides thereof which face in the direction which the wheel and sleeve are rotated to drive the bag-holders. The link 95 is formed at its upper end to provide an upwardly and inwardly directed extension 114, which carries at its forward end a stop-pin 50 115. The said arm 114 and the stop-pin 115 are so disposed that when the link is in its lowermost position the stop-pin is located 55 with its inner end in the path of the arms of the star-wheel and in position to engage the straight or abrupt faces thereof and stop or arrest the said wheel and the parts which rotate therewith, including the bag-holders. 60 When the reciprocating link 95 is raised upwardly by the action of the cam 100 for the purpose of carrying the actuating-pawl 91 backwardly over the ratchet-teeth 90 to engage another ratch.e.-tooth for the purpose of 65 rotating the holders during the next descent

of the link, the stop-pin is raised upwardly out of the path of the teeth of said star-wheel, as indicated in Fig. 9, in a manner to permit the gear 88 and the parts operatively connected therewith, including the holders, 70 to freely turn in the beginning of the descending movement of the link 95. The parts are so disposed that when the bag-holders have been rotated the required angular distance through the mechanism 75 described the stop-pin will be brought in position to engage one of the arms of the star-wheel, and thereby arrest the holders and the actuating parts from overthrow. Preferably the contact between the stop-pin 115 and the 80 flat faces of the arms of the star-wheel is a buffing contact. Such buffing contact may be provided by facing the flat sides of the star-wheel arms with a cushioning material 85 116, or the pin 115 may be associated with a spring to give a buffing or cushioning effect thereto when it is brought into contact with the star-wheel.

I have found that when operating the machine rapidly, and especially when operating 90 on bags made of thin material, it sometimes occurs that the frictional contact between the mouths of the bags and the holder-arms is so great as to prevent the bags being readily stripped off of the arms, with a result that 95 the bottoms of the bags are often punctured by the forward ends of the turning-arms. In order to avoid this result, I provide means for relieving the tension on the mouth of the distended bag at or before the time the arms 100 strike the bottom of the bag, thereby reducing the friction between the bag and holder-arms and facilitating the stripping of the bag from the holder-arms. A convenient mechanism for effecting this result is shown in the 105 drawings, which operates in connection with the bag-holder-actuating cam 100. For this purpose I have provided said cam with an adjustable peripheral projection in contact with which the roller 101 of the rock-shaft arm 110 97 rolls, and said projection is so located on the cam as to swing the rear end of the arm 97 slightly downwardly and the forward end of the arm 99 upwardly, thereby operating through the link 95 to slightly retire the pawl 115 91 from its engaged ratchet-tooth 90. The tension of the bag on the arms of the holders engaged thereby acts to pull said arms toward each other, thereby reducing the friction between the mouth of the bag and the arms 120 in such manner that said bag will slip readily off the arms when the turning-arms strike the bottom of the bag. Such release of the tension occurs just before the ends of the arms strike the bottom of the bag, and the 125 parts are immediately restored as soon as the bag is stripped off the holders. The supplemental cam projection herein shown is formed on a flat plate or bar 120, Figs. 9 and 11, which is attached to one flat side of the cam 130

by means of bolts 121, and said plate extends at one end beyond the periphery of the cam and is provided with a laterally-projecting part 122, that lies over the periphery of the cam, as best shown in Fig. 11. The said tension-releasing device is made adjustable, so as to be adapted to bags of various lengths, it being obvious that the release or such tension will be required later when operating on longer bags than when operating on shorter bags. For this purpose the bolts 121, which hold the plate or bar 120 in position, extend through curved slots 123 in the cam, thereby permitting angular adjustment of the projection 122 of said plate for the purpose described.

1 claim as my invention—

1. In a bag-turning machine, a bag-holder constructed to exert tension on the mouth of the bag while the bag is being turned, and means for releasing the tension on the distended bag before it is stripped from the holder to facilitate its removal.

2. In a bag-turning machine, the combination with the bag-holder constructed to exert tension on the mouth of the bag while the bag is being turned and the bag - turning arms, of means operating to release the tension on the distended bag just before it is stripped from the holder by said bag-turning arms.

3. In a bag-turning machine, the combination with bag-holding arms which are spread to distend the mouth of the bag placed thereover, of means permitting said bag-holding arms to yield toward each other preparatory to stripping the bag therefrom.

4. In a bag-turning machine, the combination with a bag-holder comprising two arms over which the mouth of the bag is placed, means for spreading the arms to stretch the mouth of the bag, and reciprocating bag-turning arms, of means operating to release the tension on the bag before it is stripped from the holder by said bag-turning arms.

5. In a bag-turning machine, the combination with a bag-holder comprising two arms over which the mouth of the bag is placed, means for spreading the arms apart to stretch the mouth of the bag, and adjustable means for releasing tension on the bag before it is stripped from the arms by the bag-turning arms, the adjustment of said tension-releasing device adapting the machine to bags of different lengths.

6. In a bag-turning machine, the combination with the bag-turning arms, and a bag-holder comprising parts which are separated to distend the mouth of a bag placed thereover, of a cam for operating the bag-holding arms, and means for releasing the tension on the distended mouth of the bag preparatory to stripping the bag from said bag-holding arms.

65 7. In a bag-turning machine, the combina-

tion with the bag-turning arms, and a bag-holder comprising parts which are separated to distend the mouth of a bag placed thereover, of a cam for operating the bag-holding arms, and a supplemental cam projection 70 carried by said cam operating to release the tension on the bag - mouth preparatory to stripping the bag from said holder-arms.

8. In a bag-turning machine, the combination with tie bag-turning arms and a bag-holder comprising parts which are separated to distend the mouth of a bag placed thereover, of a cam for operating the bag-holding arms, and an adjustable supplemental cam projection carried by said cam operating to 75 release the tension on the bag-mouth preparatory to stripping the bag from said holder-arms.

9. In a bag-turning machine, a bag-holder embracing bag-holding arms movable away 85 from each other to distend the mouth of the bag, of means for operating the bag-holder arms embracing a cam and a swinging arm operating on the cam-surface thereof, and a supplemental cam-surface that is adjustable 90 on the main cam-surface for releasing the tension on the bag.

10. In a bag-turning machine, a bag-holder comprising two rotative parts having arms which operate in pairs, means for intermittently turning said parts comprising an endwise-reciprocating link or bar, and a pawl-and-ratchet mechanism operatively connecting said rotative parts of the bag-holder and said link or bar.

11. In a bag-turning machine, a bag-holder comprising two rotative parts having bag-engaging arms operating in pairs, means for intermittently rotating said parts comprising an endwise-reciprocating link or bar, a pawl-and-ratchet mechanism operatively connecting said link or bar and the rotative parts of the holder and a cam for reciprocating said link or bar.

12. In a bag-turning machine, a bag-holder comprising two rotative parts having bag-engaging arms which operate in pairs, shafts fixed to said parts, and means for imparting intermittent rotation to said shafts comprising a shaft extending transversely across the 115 machine, intermeshing gears on the transverse shaft and the holder-shafts, a gear-pinion on the transverse shaft, a gear-wheel meshing with said pinion, and a pawl-and-ratchet mechanism operating to turn said 120 gear-wheel.

13. In a bag-turning machine, a bag-holder comprising two rotative parts having bag-engaging arms which operate in pairs, shafts fixed to said rotative parts and means for 125 imparting intermittent rotation to said shafts comprising a shaft extending transversely across the machine, intermeshing gears on the transverse shaft and the holder-shafts, a gear-pinion on the transverse shaft, a gear- 130

wheel meshing with said pinion, a rotative sleeve fixed to said gear-wheel, ratchet-teeth on said sleeve, a collar rocking on said sleeve and carrying a pawl engaging said teeth, and means for rocking the collar on said sleeve.

14. In a bag-turning machine, a bag-holder comprising two rotative parts having bag-engaging arms which operate in pairs, shafts fixed to said rotative parts and means for imparting intermittent rotation to said shafts comprising a shaft extending transversely across the machine, intermeshing gears on the transverse shaft and the holder-shafts, a gear-pinion on the transverse shaft, a gear-wheel meshing with said pinion, a rotative sleeve fixed to said gear-wheel, ratchet-teeth on said sleeve, a collar rocking on said sleeve and carrying a pawl engaging said teeth, and means for rocking the collar on said sleeve, comprising a reciprocating link connected with said collar, and a cam operating to impart endwise reciprocation to said link.

15. In a bag-turning machine, the combination with rotative bag-holders, of means for imparting intermittent rotation to said holders comprising a rotative sleeve geared to the holders, a pawl-and-ratchet mechanism operating to turn said sleeve, and a stop on said sleeve for arresting the overthrow of said holders.

16. In a bag-turning machine, the combination with rotative bag-holders carrying bag-engaging arms operating in pairs, of means for imparting intermittent rotation to the holders comprising a rotative sleeve geared to the holders, a ratchet on said sleeve, an actuating-link carrying a pawl engaging said ratchet and a stop for arresting the rotation of said sleeve embracing co-operative parts on said link and sleeve.

17. In a bag-turning machine, the combination with rotative bag-holders carrying bag-engaging arms operating in pairs, of means for imparting intermittent rotation to the holders comprising a rotative sleeve geared to said holders, a ratchet on said sleeve, an actuating-link carrying a pawl engaging said ratchet, and a stop for arresting the rotation of said sleeve embracing a star-wheel rotating with said sleeve and a stop-pin carried by said link.

18. In a bag-turning machine, the combination with rotative bag-holders carrying bag-engaging arms which operate in pairs, of means for intermittently rotating said bag-holders comprising a rotative sleeve geared to the holders, a ratchet on said sleeve, a collar rocking on the sleeve and carrying a pawl which engages said ratchet, a reciprocating link pivoted to said collar for rocking the same and a stop for arresting the overthrow of the holders embracing a stop-pin carried by said link.

19. In a bag-turning machine, the combination with rotative bag-holders carrying

bag-engaging arms which operate in pairs, of means for intermittently rotating said holders comprising a rotative sleeve geared to said holders, a ratchet carried by said sleeve, a collar rocking on said sleeve and carrying a pawl which cooperates with said ratchet, a reciprocating link for rocking said sleeve, a lever pivoted to the lower end of said link, a cam operating against the other end of said lever, and a spring applied to said lever and operating thereon in opposition to the cam.

20. In a bag-turning machine, the combination with rotary bag-holders, of means for intermittently rotating said holders comprising a rotative sleeve geared to the holders, a ratchet carried by the sleeve, a collar rocking on the sleeve and carrying a pawl which cooperates with said ratchet, a reciprocating link for rocking said sleeve, means for reciprocating said link comprising a rotative cam, a lever pivoted to the lower end of said link and operating at its other end against the cam, a spring applied to said lever and operating thereon in opposition to the cam, and means for adjusting the tension of said spring.

21. In a bag-turning machine, the combination with rotary bag-holders, of means for intermittently rotating said holders comprising a rotative sleeve geared to the holders, a ratchet carried by the sleeve, a collar rocking on the sleeve and carrying a pawl which cooperates with said ratchet, a reciprocating link for rocking said sleeve, means for reciprocating said link comprising a rotative cam, and a lever pivoted to the lower end of said link and operating at its other end against the cam, a spring applied to said lever and operating thereon in opposition to the cam, and means for adjusting the tension of said spring, comprising a rock-shaft provided with an arm arranged to operate on said spring, an adjusting-arm fixed to said rock-shaft and means for locking said adjusting-arm in different positions of adjustment.

22. In a bag-turning machine, the combination with rotative bag-holders carrying bag-engaging arms operating in pairs, of means for imparting intermittent rotation to the holders, comprising a rotative sleeve geared to said holders, a ratchet on said sleeve, an actuating-link operating a pawl engaging said ratchet, and means for backing the pawl away from the ratchet to release the tension of the bag supported by said holder-arms.

23. In a bag-turning machine, the combination with two rotative bag-holders carrying bag-engaging arms operating in pairs, shafts fixed to and rotating the bag-holders, a shaft extending transversely across the machine and geared to said bag-holder shafts, means for imparting intermittent rotation to said shafts and the bag-holders, and means for moving the bag-holders and the driving-gears thereof toward and away from each

other for adjusting the machine to bags of varying widths.

24. In a bag-turning machine, the combination with two rotative bag-holders carrying bag-engaging arms operating in pairs, shafts fixed to and rotating said holders, bearings in which said shafts are mounted, a shaft extending transversely across the machine, intermeshing gears on said transverse and holder shafts, the gears of the transverse shaft being movable endwise of the shaft, 5 means for imparting intermittent rotation to the said transverse shaft and therethrough to the holders, interlocking connections between said bearings for the holder-shafts and said gears of the transverse shaft, and means 10 for moving said bearings toward and from each other, carrying therewith the said holders, the holder-shafts and the intermeshing 15 gears of the holder-shafts and transverse shaft, comprising a right and left hand screw- 20 threaded shaft, the said bearings for the holder-shafts being provided with corresponding screw-threaded apertures through which said screw-threaded shaft extends.

25. In a bag-turning machine, the combination with two rotative bag-holders carrying bag-engaging arms operating in pairs, shafts fixed to and rotating said holders, 25 bearings in which said shafts are mounted, a

shaft extending transversely across the machine, intermeshing gears on said transverse and holder shafts, the gears of the transverse shaft being movable endwise of the shaft, 30 means for imparting intermittent rotation to the said transverse shaft and therethrough to the holders, interlocking connections between said bearings for the holder-shafts and said gears of the transverse shaft, and means 35 for moving said bearings toward and from each other, carrying therewith the said holders, the holder-shafts and the intermeshing gears of the holder-shafts and transverse shaft, comprising a right and left hand screw- 40 threaded shaft, the said bearings for the holder-shafts being provided with corresponding screw-threaded apertures through which said screw-threaded shaft extends.

In testimony that I claim the foregoing as 45 my invention I affix my signature, in presence of two witnesses, this 5th day of January, A. D. 1906.

SAMUEL T. LOCKWOOD.
